2,072,108

PRODUCTION OF LIGHT HYDROCARBONS

Eugene J. Houdry, Woodbury, N. J., assignor to
Houdry Process Corporation, Dover, Del., a
corporation of Delaware

Application September 16, 1933, Serial No. 689,694

4 Claims. (Cl. 196—52)

This invention relates to the production of light or low boiling hydrocarbons including gasoline from high boiling hydrocarbons such as crude oil, crude oil distillates, residual oils from cracking or transforming operations, tarry residues, and the like. More particularly, it involves the elimination, from time to time, by solvent extraction or otherwise, of certain undesirable components in the material undergoing treatment.

It is well known that the results obtained in the cracking or transforming of heavy hydrocarbons vary greatly with different charging stocks. For instance, transformation of liquid hydrocarbons obtained from the distillation of coal requires higher temperatures and higher pressures than is the case with natural liquid hydrocarbons, such as crude oil and its distillates. However, crude oils and their distillates or residuums show great differences as to yield and quantity and quality of light products produced. For example, given the same apparatus and the same conditions of operation, a Mid-Continent stock will give 23% gasoline, while a Pennsylvania stock gives 33% gasoline, and a special stock, such as petrolatum, gives 55% gasoline. Numerous observations and comparisons of the analyses of charging stocks and of residues after transformation and separation of light hydrocarbons demonstrate that the components which are able to be transformed into light hydrocarbons decrease in proportion with each pass through the apparatus, while the products which are not transformed increase in proportion. By segregation of components, it has been further determined that a part only are capable of being transformed, while another part is practically untouched by the transforming operation. This means that the operations on a large part of the material are practically wasted, and, what is far worse, this part has a detrimental effect on the operations themselves, because, while such part of the material is not producing the desired product, it does not remain inert but produces gases and carbon. The carbon is left on the apparatus, requiring more frequent cleaning and giving poor heat exchange, while the quality of the desired products is impaired, since the carbon deposit acts as a catalyst which has a tendency to increase the formation of gums and gummy constituents in the low boiling hydrocarbons. While such results have been recognized to a certain extent in connection with thermal cracking operations, there has been a tendency to ignore them.

When using catalytic transforming operations, such as those disclosed in certain of my copending applications involving the use of catalytic adsorptive masses made up in whole or in part of materials from the group comprising silicates of alumina or clayey materials, such for example

as activated hydrosilicate of alumina in molded form, at temperatures between 775° and 925° F., the effect of rapid carbon deposit is very serious, since the activity of the catalyst is quickly reduced and increased temperatures and pressures cannot be used without impairing the quality and/or the yield of the product. To test the matter, a residual oil from the fifth pass on Mid-Continent (Ranger) gas oil was separated, by the action of solvents, into two fractions, an aliphatic fraction and an aromatic fraction. The aliphatic fraction had the following characteristics:

Specific gravity	0.8179	15
Distillation (IBP)	458	
5%	500	
10%	507	
15%	513	
20%	517	10
30%	526	
40%	535	
50%	542	
60%	554	
70%	565	
80%	578	20
90%	601	
Dry point	639	
Residue	2.5%	

When subjected to the catalytic transforming operation, it produced a good yield of gasoline with a very small deposit of coke or carbon on the catalyst. The ratio of gasoline production to coky deposit was 23.71:1, and the ratio of gasoline to gas was 5.63:1. No attempt was made to secure the highest yield, since the purpose of the experiment was to check the action of the catalyst on both fractions under the same conditions. Nevertheless, the gasoline produced was 20% of the aliphatic fraction.

The aromatic fraction had the following characteristics:

Specific gravity	0.9792	
Distillation (IBP)	443	
5%	471	45
10%	481	
15%	492	
20%	499	
30%	508	
40%	524	50
50%	536	
60%	550	
70%	571	
80%	607	
90%	659	55
Dry point	676	
Residue	5.5%	

When treated under exactly the same conditions as the aliphatic fraction, the aromatic fraction

gave a yield of only 1.9% gasoline. The ratio of gasoline to coky deposit was 0.94:1, and the ratio of gasoline to gas 1.68:1. The aromatic fraction left as poison a coky deposit on the catalyst amounting to 2.02% of the mass in producing less than that percentage of gasoline, while, with the aliphatic fraction, the coky deposit was 0.78% in producing 20% gasoline. If we consider that the stock contained 45% in volume of the aliphatic fraction and 55% of the aromatic fraction, it is evident that processing of the entire stock would give a greatly decreased yield of gasoline over that resulting from the separate treatment of the aliphatic fraction, due to the fact that the catalyst would have been rapidly poisoned by the heavy deposit of coke from the aromatic fraction.

However, other experiments indicate that in a virgin stock, such as crude petroleum or distillates in the form of side cuts from a skimming or topping operation, a considerable percentage of the aromatic fraction is capable of being transformed by a catalytic operation of the type herefore described, into gasoline, but that the residual oil from the first transformation, as well as residual oils from later passes, contain aromatic fractions which are of the kind described in the preceding paragraph, namely, very refractory and breaking up only into coke and gas. Accordingly, the invention involves a transforming or cracking operation on crude oil distillates, followed by solvent or other treatment of residual material to separate and discard the unfavorable components, the later transforming operations being conducted in each instance upon the favorable constituents only. If the bottoms from the skimming or topping operation are to be transformed, or if the distillates are mixed with the bottoms, it is preferable to first submit this material to extraction of the heavier constituents, since the asphaltic and tarry materials are often detrimental to catalytic transforming masses, especially the activated hydrosilicate of alumina referred to above. Any known or suitable methods may be utilized to make a more or less complete separation of the desirable and the undesirable constituents of the stock to be transformed. The use of solvents is effective. A certain amount of separation is also possible by purely physical means, as by fractionation.

In order to illustrate the invention and the manner of its application, drawings in the form of flow charts are provided, in which:

Fig. 1 shows one way or flow chart for transforming crude oil; and

Fig. 2 shows an alternate way or flow chart. In Fig. 1, the crude petroleum is first subjected to a topping operation and the products separated into straight run gasoline, one or more side streams such as a middle or gas oil cut, and bottoms. The straight run gasoline is set aside for use or for blending with the gasoline produced in the subsequent transforming operations. The middle cut or side stream is subjected to a transforming or cracking operation, preferably the catalytic treatment at 775° to 925° F., at low or atmospheric pressure, and in contact with activated hydrosilicate of alumina in molded form, as previously specified. The gasoline resulting from this operation is set aside or blended with the previous straight run gasoline. The residual material is then subjected to a solvent or other treatment to remove the constituents unfavorable to further transforming operations. At this time, the bottoms, as indicated by the broken line *a* on the chart, may be added to the residual

material from the first transforming operation just prior to the solvent or other treatment; or a preferred way is indicated by solid lines, in which the bottoms are subjected to a separate solvent or other treatment on account of the large content of asphaltic and tarry material which normally will require a somewhat different treatment than that given to the residual oil from the transforming operation. The favorable constituents from this treatment would be added to the middle cut in advance of the transforming or cracking operation as by the solid line *b* on the chart, or to the favorable constituents from the transforming operation as by the solid line *c* and both then subjected to a second pass or catalytic transforming operation. The resulting gasoline is set aside or blended with the previously segregated gasoline. The residual material is subjected to a solvent or other treatment to discard unfavorable constituents; the favorable constituents are subjected to another pass or catalytic transforming operation; and the process may continue until the desired yield of gasoline is secured.

The operation indicated in Fig. 2 distinguishes from that just described in that there are but two products of the topping operation, namely, the straight run gasoline and residual material, no side cut in the gas oil boiling range being taken. The residual material, containing a considerable quantity of asphaltic and tarry constituents, is subjected to a solvent or other treatment to eliminate, so far as possible, the heavy constituents and aromatic components. The favorable constituents, comprising the aliphatic fraction, are then subjected to a catalytic transforming operation of the described type. The gasoline and other light products are segregated from the residual material, and the latter is subjected to another solvent or other treatment to remove the unfavorable constituents, whereupon the favorable constituents are subjected to a second pass or catalytic transforming operation, followed by a separation of products into gasoline and residual material, the process being continued until the desired yield of gasoline is produced.

Any known means for effecting the solvent or other separation of desirable and undesirable components may be utilized, the object being to discard, so far as possible, from subsequent catalytic transforming operations, the heavier and more refractory components, including the aromatic fraction. Various solvents have been proposed, especially in connection with the treatment of lubricating oils, which are capable of forming a two-layer system and are suitable for this purpose. One layer will be more aromatic and the other more aliphatic than the original oil. Among the solvents which are useful in applying the present invention are liquid SO₂, ethylene chlorhydrin, glycol mono-acetate or di-acetate, glycol monoethyl ether, glycerol, di- or tri-acetate, lactic acid nitril, di-ethyl-tartrate, furfural, aniline, toluidine, phenylhydrazine, etc. A certain degree of separation is also possible by fractionation into close cuts and by a judicious combining of the cuts.

I claim as my invention:

1. The process of producing light or low boiling hydrocarbons from crude oil or the equivalent which comprises topping the crude oil to remove the straight run gasoline and dividing the remainder by fractionation into a middle cut and bottoms, removing from the bottoms at least a part of the asphaltic and tarry aromatic constitu-

ents, adding the remaining or favorable parts to the middle cut, transforming the resulting middle cut mixture to produce the desired light products and a residual oil, removing from the residual oil at least some of the more aromatic constituents thereof, unfavorable to further transformations, and transforming the remaining or favorable parts from the residual oil into the desired light products and a residual oil suitable for a further 10 removing and transforming operation.

2. The process of producing light or low boiling hydrocarbons from crude oil or the equivalent which comprises topping the crude oil to remove the straight run gasoline, catalytically transforming a middle cut from the topping operation to produce the desired light products and a residual oil, removing from the residual oil at least some of the aromatic constituents unfavorable to further transformations by solvent treatment, catalytically transforming the remaining or favorable parts of the residual oil into the desired light products and a residual oil suitable for further removing and transforming operations, removing from the bottoms from the topping operation at least a part of the asphaltic and tarry constituents by solvent treatment in a step separate and distinct from the first removing step, and adding the remaining or favorable parts of the last removing step to the favorable parts from the first removing operation in advance of the second transforming operation.

3. The process of producing light or low boiling hydrocarbons from crude oil or the equivalent which comprises topping the crude oil to remove the straight run gasoline, transforming a middle cut from the topping operation to produce gaso-

line and a residual oil by the action of an adsorptive contact mass of the clay type, adding the bottoms from the topping operation to the residual oil, removing from the combined residual oil and bottoms some of the more aromatic constituents thereof, which rapidly impair the activity of the contact material, and transforming the remainder or favorable portion of the residual oil and bottoms by the action of an adsorptive contact mass of the clay type into the desired 10 light products and residual oil.

4. The process of producing light or low boiling hydrocarbons from crude oil or the equivalent which comprises topping the crude oil to remove the straight run gasoline, transforming a middle cut from the topping operation at low pressure and temperature into the desired light products and a residual oil in the presence of an adsorptive contact mass composed in whole or in part of activated hydrosilicate of alumina, removing from the residual oil at least a part of the constituents unfavorable to further catalytic transformations including the aromatics, transforming the remaining or favorable parts of the residual oil in the presence of contact mass of the same type 25 as the aforesaid into the desired light products and a second residual oil suitable for further removing and transforming operations, removing from the bottoms from the topping operation at least a part of the asphaltic and tarry aromatic 30 constituents, and adding the remaining or favorable part of the last removing step to one of the aforementioned favorable portions in advance of transforming the same.
